TO HEMPHILL COMPANY, OF CENTRAL FALL, RHODE ISLAND, A CORPORATION OF
MASSACHUSETTS

HORIZONTAL STRIPING ATTACHMENT FOR CIRCULAR KNITTING MACHINES

Application filed August 13, 1928. Serial No. 129,074.

This invention relates to so-called horizontal striping attachments for circular knitting machines. hosiery, it is obviously not limited to this class of work.

In order that the principle of the invention may be readily understood, one embodiment thereof is disclosed in the accompanying drawings, wherein—

Fig. 1 is a front elevation of a circular knitting machine having the striping attachment applied thereto;

Fig. 1a is a detail in side elevation of a portion of the main pattern chain and a co-operating pawl;

Fig. 2 is a left hand end elevation of the machine and the striping attachment applied thereto;

Fig. 3 is a right hand end of said machine and said attachment;

Fig. 4 is a rear elevation of the said machine and said attachment;

Fig. 5 is a plan view of a part of the shaft at the rear of the machine carrying certain controlling elements; and

Fig. 6 is a side elevation of the structure shown in Fig. 5.

In accordance with the invention, improved means are provided whereby so-called horizontal stripes of any desired width may be knitted and particularly whereby such stripes may be knitted upon so-called seamless or circular knit hosiery. Said so-called horizontal stripes extend circumferentially about the stocking and may vary in width from one course to any desired multiple thereof.

While the invention is not limited in its use to any particular type of rotary knitting machine, it is peculiarly adapted for use upon the so-called Banner knitting machine, one type of which is shown in the patent to Joshua D. Hemphill, No. 933,433, September 7, 1909, and therefore, without limiting the invention thereto, the attachment is illustrated as applied to a Banner machine, and is so described.

It is unnecessary to describe at length the said Banner machine. In this type of machine the needle cylinder rotates while the cams remain stationary, and, although the machine is for the purpose of producing

Generally speaking, the machine includes a rotating needle cylinder 1 mounted upon a suitable table 2 constituting a part of the frame of the knitting machine and, as is customary in this type of machine, said cylinder is arranged to be rotated to form the leg and foot and to be reciprocated to form the heel and toe of the stocking.

The means for effecting the rotary and reciprocating movements are substantially the same as those shown and described in the said Hemphill patent and, being well known, require no further description.

A plurality of yarn feeding elements are provided at the usual position characteristic of the Banner machine, and a series of said elements is indicated at 3 in Fig. 4. Desirably as many as four or five yarn guides may be mounted side by side at the same place, each to introduce its yarn or thread as called for by the controlling cams, as, for example, for the leg, the heel and toe, and the foot, etc. All said yarn guides are pivoted upon the latch ring 4, itself suitably pivoted so that it may be swung up out of action to afford access to the needles or for any other purpose. Since the particular type of machine here shown is the latch needle type, the member 4 is represented as a latch ring, but if the machine be equipped with spring beard needles, as may be done within the scope of the invention, then the member 4 is in the form of a partial ring, as well understood in this art.

As many as desired of the said yarn guides or yarn fingers may be controlled by the striping attachment which is the subject of this invention. For the purpose of this disclosure, but three of the yarn guides are represented as controlled by said striping attachment, but it is clearly to be understood that any greater or any less number may be so controlled.

Each of the said yarn guides or fingers is normally pressed or urged out of action in the general manner disclosed in the said Hemphill patent, as by a series of levers suitably mounted upon a standard rising from

the bed plate 2, suitable springs being employed for the purpose of moving the yarn guides respectively down into feeding position. Such movement downward into position is opposed and overcome at times by means including levers and also connecting wires, a portion of which latter is indicated at 5 in Fig. 3. At their lower ends the said wires are connected to the usual levers at the front of the machine as indicated at 6 in Fig. 1. The said levers respectively ride upon suitable cams indicated at 7 upon a drum 8 upon the cam shaft 9 in a manner not necessary herein to describe, as it is desirably similar to the construction shown in the said Hemphill patent. Assuming that there are five levers in the said group, as here shown, it is evident that, according to the dictates of the cam 7 upon the disk or drum 8, the said 15 yarn guides or fingers are permitted to act in suitable order, as, for example, to supply a yarn or thread for the leg of the stocking, another for the heel, another for the foot, etc., and for splicing. 20 Each of the said yarn guides supplies its yarn or thread in proximity to the knitting point, and each yarn so taken is desirably knitted upon all the needles in action, though obviously the machine to which this invention is to be applied may be one where there are stitch variations. In other words, the attachments of this invention is not restricted in its application to a plain machine. 25 The machine is provided with the usual driving shaft 10 having the customary pulleys 11, and in the rear thereof with a shaft 12 driven from the shaft 10 and having fast thereon the large gear 13 known as the "104 gear". Controlled from the shaft 12 is the usual quadrant 14 pivoted at 15 and operated in a manner not herein necessary to describe in effecting the reciprocation of the needle cylinder in forming the heel and toe. These parts, being desirably of customary construction, here need not further description. 30 The machine is provided with the usual narrowing pickers mounted as customary upon blocks indicated generally at 16, 16 in Fig. 3 and with the customary widening pickers mounted upon the bracket 17 shown in Fig. 2. 35 Having thus referred to the main parts of the usual mechanism of the plain or rotary Banner machine, it is pointed out that the present invention, shown for convenience as applied to such type of machine, is concerned particularly with the formation of circumferentially extending or so-called horizontal stripes in the hose or stocking, that being the type of fabric to which the invention is peculiarly applicable, but to which the use of the invention is not restricted.

The said machine is provided with the usual main pattern chain 18 suitably carried upon the main cam shaft 9 and driven

in the manner customary to the said Banner machine, as shown, for example, in the patent to Landry, No. 1,169,655, dated January 25, 1916. The said chain travels in a step-by-step manner and is of such length as to control the knitting of the stocking course by course throughout the entire extent thereof. As disclosed, the said chain is impelled forward once to every four revolutions of the needle cylinder 1.

It is to be understood that the yarn guides or fingers are under the primary control in the Banner machine of the series of cams 7 which are removably mounted upon the pattern drum 8 and act upon the levers 6. For the purpose of the present invention the said levers 6, or certain of them, control the corresponding yarn guide or guides during the knitting of the heel and the toe, but for making a horizontally or circumferentially striped stocking, such portions of the cams 7 as would control the levers 6 during the formation of the leg and the foot are removed from the drum 8, and the yarn guides are controlled from the attachment to which the invention more particularly relates, which will now be described.

The front or main pattern chain 18 functions as usual and is also employed to start the striping or rather, to release the mechanism which governs or controls the striping, but the striping is stopped or terminated by the auxiliary mechanism or attachment herein disclosed, which acts to govern or control the striping. In this manner, a wider range is given than customary to the extent of the striping, particularly with reference to the narrowness or width thereof.

Furthermore by a small compact mechanism we obtain a more varied pattern than heretofore, and may make a stripe which is a single course in width or which may be of any greater number of courses, as will be clear to those skilled in the art.

In the disclosed embodiment of the invention, there is provided at the back of the machine a shaft carrying thereon the following parts, namely: an auxiliary drum having cams controlling levers which individually control the several yarn guides; a ratchet actuated as hereinafter described from the "104 gear"; a disk which controls the binder so as to open and receive and close whenever a change of stripping yarn is made; and a sprocket over which passes the auxiliary pattern chain. The pawl by which the said ratchet is actuated is released for action as hereinafter described by the main pattern chain, and according to the arrangement of links upon the main pattern chain and the auxiliary pattern chain, the striping is started and stopped. The said pawl is, however, itself actuated from the "104 gear".

Referring more particularly to the mechanism herein shown, the "10 $\frac{1}{2}$ gear" 13 re-

ceives thereon a nearly annular plate 18' as shown most clearly in Fig. 2. Said plate 18' has a gap 19 permitting the plate to be slipped into place by an upward sliding movement, and when in position it is secured flatwise against a face of the "104 gear", and is capable of being circumferentially adjusted by reason of the curved slots 20—20 receiving the screws or bolts 21, 21 from the "104 gear".

Upon the said plate 18' are provided a suitable number of pins or rolls 22, here shown as two in number. If desired, four equally positioned or any other suitable number of these pins or rolls may be provided.

The "104 gear", with the attached plate 18', rotates one revolution to four revolutions of the needle cylinder, and if for example four equally spaced pins 22 be employed upon the plate 18', there is thus provided one pin for each course, so that a complete rotation of the said plate 18' causes each of the four pins to function. Since in the disclosed embodiment of the invention but two pins 22 are employed, it is evident that for a single revolution of the "104 gear", two impulses will be imparted to the part actuated thereby, if said part be in position to be so actuated. From a suitable part of the frame and desirably from the under side of the bed plate 2, there is pivotally supported a depending rod or actuator 23. For this purpose, there is provided a bracket 24 to which the said rod or actuator is hinged or pivoted at 25.

Secured to or forming a part of said rod or actuator, there is provided a cam 26 which is shaped as shown most clearly in Fig. 2. Viewing said figure, the rotation of the "104 gear" is in a clockwise direction, so that each pin 22 in turn engages the edge of the cam 26, and thereby swings the pivoted rod or actuator 23. The shape of the cam 26 beginning at its lower end is such that when a pin 22 engages the same, the said rod 23 begins to move slowly from the left viewing Fig. 2, and then to gain speed very rapidly up to about the middle of the cam and from there upward the speed tapers off gradually to nothing. The upper portion of the cam, as indicated at 27, is curved or inclined toward the right viewing Fig. 2, so as to control the return swinging movement of the rod 23. This prevents said rod from returning to the right with a jar and insures an even or smooth return movement. Desirably there is also provided a strip or member 28 horizontally extending from the large or main bracket 29, and having a right angled or bent end 30 which acts as a stop to prevent the pivoted rod 23 from swinging too far toward the right viewing Fig. 2. Said strip 28 is provided with a longitudinal slot 31 and is held in place by a bolt or rod 32 in a lengthwise slot 33 in the bracket 29. The return movement of the pivoted rod 23 is produced

by the coiled spring 33' secured thereto and to a suitable part of the framing.

At its lower end the pivoted rod or actuator 23, as shown most clearly in Fig. 6, is provided with a pawl 34 pivoted thereto at 35 and adapted to engage with the teeth 36 of a ratchet 37 fast upon the shaft 38. The said shaft is suitably supported herein, by means of a bracket 39 (Fig. 2) having a web or part which is secured flatwise against the main or large bracket 29. Upwardly extending from the body portion of the bracket 39 are members 40, 41 having bearings wherein the said shaft 38 is received for rotation. Preferably a brake 41a (see Fig. 4) is adapted to bear at all times upon a face of the ratchet 37, it being pivoted at 41b upon a bracket on the framing and spring pressed against said face of the ratchet.

The said shaft 38 has also fast thereon a disk like drum 42 which is provided with a number of circumferentially extending cams indicated at 43 and which in number correspond to the number of yarn guides or fingers that are to be controlled for striping. Any number of yarn guides or fingers may be so controlled, as, for example, five, in the Bannér machine. Herein for the purpose there are represented three levers 44 so controlled, and it will be observed from Figs. 2, 3 and 4 that said levers are co-axially mounted upon a horizontal pivot so as to extend horizontally toward the front of the machine where each of them is connected to the appropriate wire 5. The cams 43 are preferably composed or made up of short blocks or pieces individually secured as by means of screws 45 to the periphery of the drum 42. When one of the levers 44 rests upon a cam portion 42 the yarn guide or finger pertaining thereto is out of action, but when a lever 44 rests in a space circumferentially between blocks 43 of any one cam path or track, that is, when it rests upon the surface of the drum 42—the yarn guide or finger pertaining thereto is in action, and striping is effected by means of the yarn or thread so supplied.

Also fast upon the shaft 38 is a disk 46 having suitable cam portions 47 secured thereto to ride under and actuate a lever 48 which is pivoted at 49, as most clearly shown in Fig. 2, and at 50 is suitably connected to the rod or link 51 which is actuated in usual manner as by the lever 52 from a cam upon the pattern drum and extends upward to the binder mechanism 53 which is not here shown in detail, but which is or may be of the usual type upon the Banner machine. The construction and operation are such that whenever a yarn or thread that has been employed in striping is being changed, the binder is opened to receive the withdrawn yarn or thread and instantly closes to hold the same.

Fast upon the left hand end of the shaft 38, 120

viewing Fig. 4, is a sprocket 54, shown most clearly in Figs. 3, 5 and 6, and which receives the auxiliary sprocket or pattern chain 55 composed of links, desired ones of which have projections or lugs 56. The said pattern or sprocket chain 55 extends downwardly to and passes about a small sprocket wheel 57 pivoted at 58 upon the large bracket 29, as most clearly shown in Fig. 3.

- 6 The said lugs 56 traveling, as they do, in a clockwise direction viewing Figs. 3 and 6, pass under the downwardly extending end or tooth 59 upon a lever 60 pivoted at 61 upon the framing and provided with a coiled spring 62 connected thereto at 63 and also connected at 64 to a part to be hereinafter referred to. The said coiled spring 62 tends to hold the tooth or end 59 of the lever 60 down in position to be engaged by a lug 56 of the chain 55 and to be elevated thereby.
- 10 The under edge of the lever 60 is provided with a cutout portion 65 providing a tooth or projection 66 with a shoulder 67. The lever 60 constitutes a catch or latch, the shoulder 67 being the part thereof functioning as a catch or latch, and the lugs 56 upon the auxiliary pattern chain 55 act in turn to elevate the lever 60, thus withdrawing the catch or latch-shoulder 67 from its functioning position so as to release a part now to be described.
- 15 The under edge of the lever 60 is provided with a cutout portion 65 providing a tooth or projection 66 with a shoulder 67. The lever 60 constitutes a catch or latch, the shoulder 67 being the part thereof functioning as a catch or latch, and the lugs 56 upon the auxiliary pattern chain 55 act in turn to elevate the lever 60, thus withdrawing the catch or latch-shoulder 67 from its functioning position so as to release a part now to be described.
- 20 The under edge of the lever 60 is provided with a cutout portion 65 providing a tooth or projection 66 with a shoulder 67. The lever 60 constitutes a catch or latch, the shoulder 67 being the part thereof functioning as a catch or latch, and the lugs 56 upon the auxiliary pattern chain 55 act in turn to elevate the lever 60, thus withdrawing the catch or latch-shoulder 67 from its functioning position so as to release a part now to be described.
- 25 The under edge of the lever 60 is provided with a cutout portion 65 providing a tooth or projection 66 with a shoulder 67. The lever 60 constitutes a catch or latch, the shoulder 67 being the part thereof functioning as a catch or latch, and the lugs 56 upon the auxiliary pattern chain 55 act in turn to elevate the lever 60, thus withdrawing the catch or latch-shoulder 67 from its functioning position so as to release a part now to be described.
- 30 The under edge of the lever 60 is provided with a cutout portion 65 providing a tooth or projection 66 with a shoulder 67. The lever 60 constitutes a catch or latch, the shoulder 67 being the part thereof functioning as a catch or latch, and the lugs 56 upon the auxiliary pattern chain 55 act in turn to elevate the lever 60, thus withdrawing the catch or latch-shoulder 67 from its functioning position so as to release a part now to be described.
- 35 The under edge of the lever 60 is provided with a cutout portion 65 providing a tooth or projection 66 with a shoulder 67. The lever 60 constitutes a catch or latch, the shoulder 67 being the part thereof functioning as a catch or latch, and the lugs 56 upon the auxiliary pattern chain 55 act in turn to elevate the lever 60, thus withdrawing the catch or latch-shoulder 67 from its functioning position so as to release a part now to be described.
- 40 The under edge of the lever 60 is provided with a cutout portion 65 providing a tooth or projection 66 with a shoulder 67. The lever 60 constitutes a catch or latch, the shoulder 67 being the part thereof functioning as a catch or latch, and the lugs 56 upon the auxiliary pattern chain 55 act in turn to elevate the lever 60, thus withdrawing the catch or latch-shoulder 67 from its functioning position so as to release a part now to be described.
- 45 The under edge of the lever 60 is provided with a cutout portion 65 providing a tooth or projection 66 with a shoulder 67. The lever 60 constitutes a catch or latch, the shoulder 67 being the part thereof functioning as a catch or latch, and the lugs 56 upon the auxiliary pattern chain 55 act in turn to elevate the lever 60, thus withdrawing the catch or latch-shoulder 67 from its functioning position so as to release a part now to be described.

In order to hold the lower end of the depending rod or actuator 23 forward (that is, to the right viewing Figs. 3 and 6), so that it will not be engaged and actuated by a pin or roll 22 on the plate 18 (which would result in terminating the striping by the then active yarn guide or pin), there is provided a pawl stop 68, shown most clearly in Figs. 3 and 6. Said pawl stop 68 in its holding or restraining position presents its inner edge 69 close against the rear edge of the depending rod or actuator 23, when the latter has moved forward to turn the ratchet controlled thereby one tooth.

It will be evident that if the depending rod 23 were free to be pulled to the left by the coil spring 33', said depending rod would be moved again to the right by the next pin or roll 22 on the plate 18, and the striping by the then active finger would terminate. Means are therefore employed to prevent said depending rod 23 from returning to a position where it can be engaged and actuated by a pin or roll 22 until it is desired to change the striping, and this change in or terminating of the striping is under the control of the lugs 56 upon the sprocket chain 55.

The said pawl stop 68 is pulled back by a series of levers now to be described, thereby to release the parts to permit the striping to begin.

The said pawl stop 68 is carried by a lever arm 70 pivotally but loosely mounted upon the shaft 38. Pivotally connected to said

lever 70 between its ends, as at 71, there is provided a link 72 capable of being varied in length by reason of the slots 73 and screws 74, shown in Fig. 3. Said link at its lower end is pivotally connected at 75 to a horizontally arranged lever 76, to which the said coil spring 62 is connected. Said lever 76 is pivoted upon the bracket 77 to a part of the framing, and said lever 76 has pivotally secured thereto at 78 an upwardly extending link 79, which is pivotally secured at 80 to a member or finger 81, shown most clearly in Figs. 1a and 3, and which is pivoted at 82 upon the framing. The said member or finger 81 has formed therewith or secured thereto a tooth 83 having a sharp edge 84 adapted to ride over (but not to rest upon) a lug 85 upon the main pattern chain 18, which lug 85 is also provided with a sharp edge.

From the fact that the front member or finger 81 with its tooth 83 does not at any time rest upon the top of a lug 85 of the pattern chain 18, it follows that the pawl stop 68, 69 may be released on any forward movement of the stripper mechanism, and there is thus no necessity for a prolonged wait, such, for example, as for four movements thereof. The purpose of providing the connection from the pawl stop 68, 69 to the front chain 18 is to provide means to pull back or withdraw the pawl stop 68, 69 into a position where it can again be engaged by the shoulder 67 of the latch or catch, so as again to allow the stripper to operate. In other words, when the pawl stop 68, 69 is engaged by the shoulder 67, it is then held so far to the left viewing Figs. 3 and 6, that it cannot restrain the depending rod or actuator 23 from being moved to the left by the coil spring 33', which therefore brings said depending rod 23 into a position where it may be struck by the next pin or roll 22 upon the plate 18, and thereby be caused to turn the ratchet 37 one tooth.

The said pawl stop 68, 69, as shown most clearly in Fig. 4, is of a general right angular form, and in the construction shown the pawl stops 68, 69, which is secured to the upper end of the lever 70, directly engages the back face of the said depending rod 23, thereby at the proper time holding the pawl 34 thereon forward or to the right viewing Figs. 3 and 6, thus, as stated, preventing said pawl from being carried inward by the spring 33', so as to engage another tooth of and impart further movement to the ratchet 37 before the desired time, and therefore the striping continues. When, however, the tooth 66, with its shoulder 67, engages with the pawl stop 68, 69, the pawl with its depending rod 23 may be moved inward by the coil spring 33', and the next pin or roll 22 upon the plate 18 will act upon the cam 26 on said depending rod 23, and thereby actuate said depending rod and pawl to impart another stepped

movement to the ratchet 37, which results in a change in the horizontal striping, which change, therefore, is governed or controlled by the "104" gear.

Referring again to the member or finger 81 at the front of the machine, it is to be understood that the lugs 85 are provided upon special links, as inasmuch as the tooth 83 never rests upon the top of a lug 85 (but on the contrary the tooth 85 rides without pause up, over and down the lug 85), the result is to bring the pawl stop 68, 69 back or inward, viewing Figs. 3 and 6, so that said pawl stop 68, 69, is thereby positioned back of and is held by the shoulder 67 on the catch or latch 60, and said pawl stop 68, 69 will stay in this position unless and until said catch or latch 60 is again lifted by a projection 56 on a lug of the rear sprocket chain 55, in which event the horizontal striping is terminated.

The construction, particularly if there be four pins on the 104 gear, as already referred to, is such that a stripe may consist of a single course or of two, three or more courses. A movement of the ratchet 37 to the extent of two teeth is necessary to make a single course, namely, a movement one tooth to throw in the desired yarn and a movement of another tooth to throw it out. A single movement of the pawl 34 moves the auxiliary chain 55 two links. Inasmuch as by the described construction a tooth may be moved at longer or shorter intervals as desired, it is evident that each stripe may be of any desired width. Each series of stripings is initiated from the front or main chain which through the described connections 72, 76, 79, 81, etc. pulls back the pawl stop 68, 69, this action releasing the striping mechanism. A lug 56 upon the auxiliary pattern chain terminates the striping.

The main or body yarn of the stocking or other fabric is, of course, replaced by a striping yarn when striping is to be effected, the striping yarn being therefore a substitute and not a reinforcing yarn. When striping is to begin, a lug 85 upon the front or main chain lifts the special member or finger 81 and immediately lets it again fall, but the lifting movement acts to pull inward or rearward the pawl stop 68, 69, as already described, thus starting the color striping by releasing the mechanism which governs or controls the same. The pawl stop 68, 69 having been pulled back or inward, the depending rod 23 with its pawl 34 can be operated by the next roll or pin 22 to turn the shaft 38, and the parts mounted thereon which therefore function as already described to make whatever stripes are indicated and provided for by the arrangement of pins on the pattern drum 42 (Fig. 4). This striping continues until the next lug 56 on the chain 55 comes into action and lifts the said latch or catch 60 so as to terminate

the striping, whereupon the main body yarn or some other color of yarn is instantly brought into action as a substitute yarn, this depending upon the arrangement of the cams 43 upon the auxiliary drum 42. It will be understood that so long as the pawl stop 68 is held back by the latch 60, the striping continues, and during that period the changes in the stripes are effected by the pins on the "104" gear whereby through the actuator 23 the pattern drum 42 is turned step by step.

With two pins or rolls 22 upon the plate 18, the stripes would be at the minimum two courses in width, but if four equally spaced pins be employed, each stripe might at the minimum be one course in width.

The front set of leaves 6 are practically non-functioning during the formation of the leg and foot, and this is effected, as stated, through the removal of the necessary cams from the drum 8. Sufficient cams are, however, left upon the drum 8 to control the necessary front levers for the heel and the toe.

Having thus described one embodiment of the invention, I desire it to be understood that although specific terms are employed, they are used in a generic and descriptive sense and not for purposes of limitation, the scope of the invention being set forth in the following claims.

I claim:

1. A horizontal striper attachment for circular knitting machines comprising in combination, a series of yarn guides adapted to be moved into and out of feeding relation with respect to the needle circle, a primary pattern chain member at the front of the machine whereby the said yarn guides may be primarily controlled, and auxiliary controlling means for said yarn guides at the rear of the machine, said auxiliary controlling means including a gear driven at a fixed ratio with respect to the rotation of the knitting head and having spaced impulse-giving members thereon, an actuator pivotally carried by the machine and depending into position to be swung by said impulse-giving members, a shaft at the rear of the machine, a pattern drum carried by said shaft, lever connections between said pattern drum and a plurality of said yarn guides, an auxiliary pattern member also carried by said shaft, and having spaced indicating parts, a ratchet also carried by said shaft, a pawl carried by said depending actuator and adapted periodically to actuate said ratchet, a latch member adapted to be released by the indicating parts upon said auxiliary pattern member, a pawl stop adapted in one position to hold said depending actuator from engagement by said impulse-giving members upon said gear, and adapted in another position to be held by said latch member, and means connecting in operation the said pawl stop and the said primary pat-

tern chain member, whereby said pawl stop is moved from engagement with the actuator and into latching engagement with the latch by said primary pattern chain member, thereby releasing said actuator to initiate the horizontal striping.

2. A horizontal striper attachment for an independent needle, circular, knitting machine, wherein the needle cylinder is rotated, comprising in combination, a series of yarn guides adapted to be moved into and out of feeding relation with respect to the needles, a primary pattern chain at the front of the machine whereby the yarn guides may be primarily controlled through operative connections, and auxiliary striper controlling means for a plurality of said yarn guides, at the rear of the machine, said auxiliary striper controlling means including a gear driven at a fixed ratio with respect to the rotation of the needle cylinder, and having spaced impulse-giving pins thereon, an actuator rod pivotally carried by the framing, and depending into position to be swung by said pins, a shaft at the rear of the machine, a pattern drum carried by said shaft and having circumferentially arranged cams, lever and link connections between said cams upon the pattern drum and a plurality of said yarn guides, an auxiliary pattern chain also carried by said shaft and having spaced lugs, a ratchet also carried by said shaft, a pawl carried by said actuator rod and adapted periodically to actuate said ratchet, a latch member pivotally mounted upon the frame and adapted to be swung and thereby released by the lugs upon said auxiliary pattern chain, a pawl stop adapted in one position to hold said depending actuator rod from impulse by said pins upon said gear, and adapted in another position to be held by said latch member out of functioning relation to said actuator rod, a member at the front of the machine having a lug to be engaged and moved by lugs upon the primary pattern chain, and link and lever connections between a hereinbefore mentioned pawl and said pawl stop, whereby striping is initiated from the primary pattern chain and is terminated by the auxiliary pattern chain.
3. A horizontal striper attachment for an independent needle, circular, knitting machine, wherein the needle cylinder is rotated, comprising in combination, a series of yarn guides adapted to be moved into and out of feeding relation with respect to the needles, a primary pattern chain at the front of the machine whereby the yarn guides may be primarily controlled through operative connections, and auxiliary striper controlling means for a plurality of said yarn guides, at the rear of the machine, said auxiliary striper controlling means including a plate adapted to be secured to a gear of the machine which is driven at a fixed ratio with respect to the rotation of the needle cylinder, said plate

having spaced impulse-giving pins thereon, an actuator rod pivotally carried by the framing and depending into position to be swung by said pins, a shaft at the rear of the machine, a pattern drum carried by said shaft and having circumferentially arranged cams, lever and link connections between said cams upon the pattern drum and a plurality of said yarn guides, an auxiliary pattern chain also carried by said shaft and having spaced lugs, a ratchet also carried by said shaft, a pawl carried by said actuator rod and adapted periodically to actuate said ratchet, a latch member pivotally mounted upon the frame and adapted to be swung and thereby released by the lugs upon said auxiliary pattern chain, a pawl stop adapted in one position to hold said depending actuator rod from impulse by said pins upon said gear, and adapted in another position to be held by said latch member out of functioning relation to said actuator rod, a member at the front of the machine having a lug to be engaged and moved by lugs upon the primary pattern chain, and link and lever connections between a hereinbefore mentioned pawl and said pawl stop, whereby striping is initiated from the primary pattern chain and is terminated by the auxiliary pattern chain.

4. A circular, independent needle, knitting machine having a series of independent yarn fingers, a primary pattern means for controlling them individually for producing each an extensive part of the article being knitted, a main drive shaft having a gear thereon, a gear in mesh with said first mentioned gear, cam means upon said last mentioned gear, an actuator moved by said cam means, an auxiliary pattern member adapted to be moved by said actuator, connections from said auxiliary pattern member to one or more of said yarn fingers for effecting horizontal striping, a latch controlled by said auxiliary pattern member, a member adapted to be controlled by said primary pattern member to prevent movement of said actuator and adapted at times to be held out of its functioning position by said latch.

5. A circular, independent needle, knitting machine having a series of independent yarn fingers, a primary pattern means for controlling them individually for producing each an extensive part of the article being knitted, a main drive shaft having a gear thereon, a gear in mesh with said first mentioned gear, cam means upon said last mentioned gear, an actuator moved by said cam means, an auxiliary pattern member adapted to be moved by said actuator, connections from said auxiliary pattern member to one or more of said yarn fingers for effecting horizontal striping, a latch adapted to be released by said auxiliary pattern member, thereby to terminate horizontal striping, a member adapted to be withheld from func-

tioning position by said latch, but when released by the latter to hold the actuator from movement, and operative connections to said primary pattern member whereby horizontal striping is initiated by said primary pattern member.

6. A circular, independent needle, knitting machine having a series of independent yarn fingers, a primary pattern means for controlling them individually for producing each an extensive part of the article being knitted, a main drive shaft having a gear thereon, a gear in mesh with said first mentioned gear, cam means upon said last mentioned gear, an actuator moved by said cam means, an auxiliary pattern member adapted to be moved by said actuator, connections from said auxiliary pattern member to one or more of said yarn fingers for effecting horizontal striping, said auxiliary pattern member including a shaft, a pattern member fixed on said shaft, a ratchet fast on said shaft, an auxiliary pattern chain supported by said shaft and having spaced lugs, and a latch pivoted upon the machine frame and adapted to be swung into released position by lugs upon said auxiliary pattern chain, a pawl stop adapted in one position to be held by said latch and in another position adapted itself to hold said actuator rod from movement, and means connecting in operation the said pawl stop and said primary pattern member, whereby said pawl stop is moved from engagement with the actuator and into latching engagement with the latch by said primary pattern member, thereby releasing said actuator to initiate the horizontal striping.

7. A horizontal striping attachment for circular knitting machines comprising in combination, a series of yarn guides adapted to be moved into and out of feeding relation with respect to the needle circle, a primary pattern chain member at the front of the machine whereby the said yarn guides may be primarily controlled, and auxiliary controlling means for said yarn guides at the rear of the machine, said auxiliary controlling means including a gear driven at a fixed ratio with respect to the rotation of the knitting head and having spaced impulse-giving members thereon, an actuator pivotally carried by the machine and depending into position to be swung by said impulse-giving members, a shaft at the rear of the machine, a pattern drum carried by said shaft, lever connections between said pattern drum and a plurality of said yarn guides, an auxiliary pattern member also carried by said shaft, and having spaced indicating parts, a ratchet also carried by said shaft, a pawl carried by said depending actuator and adapted periodically to actuate said ratchet, a latch member adapted to be released by the indicating parts upon said auxiliary pattern member, a pawl stop

adapted in one position to hold said depending actuator from engagement by said impulse-giving members upon said gear, and adapted in another position to be held by said latch member.

8. A horizontal striping attachment for circular knitting machines comprising in combination, a series of yarn guides adapted to be moved into and out of feeding relation with respect to the needle circle, a primary pattern chain member whereby the said yarn guides may be primarily controlled, and auxiliary controlling means for said yarn guides, said auxiliary controlling means including a gear driven at a fixed ratio with respect to the rotation of the knitting head and having spaced impulse-giving members thereon, an actuator pivotally carried by the machine and extending into position to be swung by said impulse-giving members, a shaft, a pattern drum carried by said shaft, lever connections between said pattern drum and a plurality of said yarn guides, an auxiliary pattern member having spaced indicating parts, a ratchet, a pawl carried by said actuator and adapted periodically to actuate said ratchet, a latch member adapted to be released by the indicating parts upon said auxiliary pattern member, a pawl stop adapted in one position to hold said actuator from engagement by said impulse-giving members upon said gear, and adapted in another position to be held by said latch member, and means for controlling said pawl stop from said primary pattern chain member.

9. A horizontal striping attachment for an independent needle, circular, knitting machine, wherein the needle cylinder is rotated, comprising in combination, a series of yarn guides adapted to be moved into and out of feeding relation with respect to the needles, a primary pattern chain whereby the yarn guides may be primarily controlled through operative connections, and auxiliary striping controlling means for a plurality of said yarn guides, said auxiliary striping controlling means including a plate adapted to be secured to a gear of the machine which is driven at a fixed ratio with respect to the rotation of the needle cylinder, said plate having spaced impulse-giving pins thereon, an actuator rod pivotally carried by the framing and extending into position to be swung by said pins, a shaft, a pattern drum having circumferentially arranged cams, lever and link connections between said cams upon the pattern drum and a plurality of said yarn guides, an auxiliary pattern chain having spaced lugs, a ratchet, a pawl carried by said actuator rod and adapted periodically to actuate said ratchet, a latch member pivotally mounted and adapted to be swung and thereby released, by the lugs upon said auxiliary pattern chain, a pawl stop adapted in one position to hold said actuator rod from impulse by said pins

upon said gear, and adapted in another position to be held by said latch member out of functioning relation to said actuator rod, a member having a lug to be engaged and moved by lugs upon the primary pattern chain, and link and lever connections between a hereinbefore mentioned pawl and the pawl stop whereby striping is initiated from the primary pattern chain and is terminated by the auxiliary pattern chain.

10. A horizontal striper attachment for an independent needle, circular, knitting machine, wherein the needle cylinder is rotated, comprising in combination, a series of yarn guides adapted to be moved into and out of feeding relation with respect to the needles, a primary pattern chain whereby the yarn guides may be primarily controlled through operative connections, and auxiliary striper controlling means for a plurality of said yarn guides, said auxiliary striper controlling means including a plate adapted to be secured to a gear of the machine which is driven at a fixed ratio with respect to the rotation of the needle cylinder, said plate having spaced impulse-giving pins thereon, an actuator rod pivotally carried by the framing and extending into position to be swung by said pins, a shaft, a pattern drum having circumferentially arranged cams, lever and link connections between said cams upon the pattern drum and a plurality of said yarn guides, an auxiliary pattern chain having spaced lugs, a ratchet, a pawl carried by said actuator rod and adapted periodically to actuate said ratchet, a latch member pivotally mounted and adapted to be swung and thereby released by the lugs upon said auxiliary pattern chain, a pawl stop adapted in one position to hold said actuator rod from impulse by said pins upon said gear, and adapted in another position to be held by said latch member out of functioning relation to said actuator rod, a member having a lug to be engaged and moved by lugs upon the primary pattern chain, and means between a hereinbefore mentioned pawl and said pawl stop whereby striping is initiated from the primary pattern chain and is terminated by the auxiliary pattern chain.

In testimony whereof, we have signed our names to this specification.

JOHN LAWSON.
